[57] CLAIM

The ornamental design for a wheeled luggage case, as shown and described.

DESCRIPTION

FIG. 1 is a perspective view taken from the front left side of a wheeled luggage case embodying our new design;

FIG. 2 is a left side view thereof;

FIG. 3 is a top view thereof;

FIG. 4 is a front view thereof;

FIG. 5 is a right side view thereof;

FIG. 6 is a back view thereof; and,

FIG. 7 is a bottom view thereof.

The broken line showing of the handle element is for illustrative purposes only and forms no part of the claimed design.
